UNITED STATES PATENT OFFICE.

EDWIN CRIPPEN AND WILLIAM KING, OF NEW ORLEANS, LOUISIANA.

SNAP-HOOK.

SPECIFICATION forming part of Letters Patent No. 380,997, dated April 10, 1888.

Application filed July 26, 1887. Serial No. 245,360. (No model.)

To all whom it may concern:

Be it known that we, EDWIN CRIPPEN and WILLIAM KING, of New Orleans, in the parish of Orleans and State of Louisiana, have invented a new and Improved Snap-Hook, of which the following is a full, clear, and exact description.

Reference is to be had to the accompanying drawing, in which the figure is a front elevation of our new and improved snap-hook.

The invention will first be described in connection with the drawing, and then pointed out in the claim.

The body A of the snap-hook is reduced at its lower end and curved to form an open hook, a, over the entrance, to which the spring b is held in the usual manner. The upper part of the body A is formed with the apertured cheek-pieces c c for attaching to the hook the shackles C D by the bolt E.

The shackle C is bent to form the apertured

plates f f, which are apertured to correspond with cheek-pieces c c to receive the bolt E, and the said shackle is designed to receive a strap, F, as shown in the drawing.

The shackle D is for attaching side straps, G, to the snap-hook, and is made U-shaped and formed with the apertured cheek-pieces h h to receive the bolt E, as shown clearly in the drawing.

Having thus fully described our invention, we claim as new and desire to secure by Letters Patent—

The combination, with the snap-hook, of the shackles C D and bolt E, substantially as described.

EDWIN CRIPPEN.
WILLIAM KING.
